UNITED STATES PATENT OFFICE.

JUNJI MASKO, OF INDIANAPOLIS, INDIANA.

FOLDING DARK ROOM.

1,074,373.

Specification of Letters Patent. Patented Sept. 30, 1913.

Application filed August 31, 1912. Serial No. 718,095.

To all whom it may concern:

Be it known that I, JUNJI MASKO, a subject of the Emperor of Japan, and a resident of Indianapolis, in the county of Marion and State of Indiana, United States of America, have invented certain new and useful Improvements in Folding Dark Rooms, of which the following is a specification.

10 My invention is an improvement in folding dark rooms for photographic purposes and has for its object the provision of a device, by means of which the development of negatives and printing of prints may be 15 done without the use of a dark room.

It is a fact that the greater portion of the pleasure found in amateur photography is in the development and finishing of one's own work. It is objectionable however, that 20 the said work, or at least a great part of it, must be done in a dark room, and there are many disagreeable features in the ordinary dark room, such as for instance, lack of ventilation, over-heat, bad odor and the 25 inconvenience of going in and out during the work.

One of the objects of the present invention is to provide a dark room that may be easily transported, and that will take up 30 but little room when in use, and wherein the worker is outside of the dark room with the exception of his hands, and wherein the hands may be removed when desired, without affecting the work.

35 In the drawings:—Figure 1 is a perspective view of the device from the rear, Fig. 2 is a central transverse vertical section, Fig. 3 is a longitudinal vertical section, Fig. 4 is a front view, Fig. 5 is an enlarged 40 detail front view of the connection between the body of the device, Fig. 6 is a vertical section of Fig. 5, and Fig. 7 is a perspective view of a portion of the frame.

The present embodiment of the invention 45 comprises a casing composed of a front plate 1, a rear frame 2, a bottom 3, a top 4, and ends 5 and 6 respectively. It will be evident that the elements 1 to 6 inclusive may be made of any suitable material, as 50 for instance, metal or wood, and that they may be made of various sizes and dimensions depending upon circumstances.

The front 1 is provided near its lower 55 end with a longitudinally extending ledge 7, the said ledge being spaced above the bottom as shown more particularly in Fig. 2.

At the upper edge the said front is also provided with a pair of spaced longitudinally extending ribs 8, the said ribs forming a guideway for receiving the adjacent edge of the top 4. The rear frame 2 is also provided with a longitudinal rib 9, at the same level as the rib 7 and the said ribs are adapted to support the bottom 3. The upper edge of the said frame is also provided with spaced longitudinally extending ribs 10, registering with the ribs 8 when the device is set up, and forming a guideway similar to that between the ribs 8 for receiving the top 4.

Each of the ends 5 and 6 is detachably connected to the front 1 and the rear frame 2 in the manner shown more particularly in Fig. 1 and Figs. 5 to 7. The end 5, or 6, as the case may be, is provided at each of its side edges with a plurality of hinge leaves 11, and the front 1 and the rear frame 2 are provided with similar hinge leaves 12, so arranged that when the ends are placed in position, the bearings of the 75 hinge leaves on the ends will register with the bearings of the hinge leaves 12 and will fit between the said bearings to receive a rod 13 which passes through all of the bearings at one side of the end.

It will be noted from an inspection of Fig. 1, that the hinge leaves at each side are arranged in alinement, so that a single rod will pass through all the bearings at one side, and each rod is provided with an eye 90 14, at its upper end for permitting the rod to be withdrawn. The upper end of each of the ends 5 and 6 is provided with spaced longitudinally extending ribs 15, forming guideways for receiving the ends of the top 95 4, and each of the said ends is also provided at each side edge with a vertically extending groove 16, which is adapted to receive a similarly shaped rib 17 on the front or rear frame, as the case may be. The said rib 100 fitting within the groove 16 prevents the entrance of light between the ends and the front and rear. Each end is also provided with a door opening 18, in which is arranged a door 19. Each door is hinged to the ends 105 as shown at 20, and is provided with a button or knob 21, for convenience in opening the same. The hinges 20 are spring hinges, so that the door will be closed automatically whenever it is released. Each of the ends 110 5 and 6 is provided with a handle 22 at its top, the said handle in the present instance

being formed from a strip or strap of leather nailed or otherwise secured to the end.

In the top 4, and at the longitudinal center and slightly nearer the rear than the front 5 of the device, an opening is provided and the said opening is encircled below the top 4 by a frame 23. The said frame is provided with a pair of vertically spaced grooves or guide-ways 24, for receiving sheets 25 of glass, the 10 said sheets 25 being impervious to the actinic rays, that is, the said sheets are preferably of ruby and orange colored glass. An eye shield 26 is inserted in the opening above the sheets of glass 25, the said shield being of 15 suitable material and having an edging or facing 27 of some soft material, as for instance, velvet. The shield 26 is shaped at its upper edge to fit across the eyes, and the opening is designed to afford a peep-hole 20 through which the operator may watch the progress of the work within the case. An opening 28 is also provided in the front 1 of the case, the said opening being preferably rectangular in shape and having an outwardly extending rib 29 encircling the same. A frame 30 encircles the opening on the inner side or face of the front 1, and the said frame is grooved on its inner face as shown 25 more particularly in Fig. 2 at 31 to receive 30 a plurality of frames 32, the said frames being three in number in the present instance and being arranged to slide longitudinally of the case. The rearmost of the frames 32 is a screen covered with orange colored 35 paper, another, a sheet of ruby glass, and the third a sheet of orange glass. The three may be arranged one behind the other in front of the opening 28 or one or more may be used, as may be desired. When handling 40 very sensitive articles, both the frames and the screen should be closed, while in ordinary cases the glass windows are alone used.

The rear frame 2 is open above the bottom 3. A hood 33 of suitable dark colored material and of the shape shown 45 in Figs. 1 and 2 is secured within the frame at the outer edge thereof, by means of tacks 34 or the like. The said hood is of bellows shape and at each end a sleeve 35 is 50 provided for receiving the hands and arms of the operator. The hood is otherwise closed, and is of dark material, impervious to light.

A blind roller or curtain 36 impervious 55 to light, is mounted at the top of the frame. The roller upon which the blind or curtain is mounted is preferably of the self-winding or spring roller type. The curtain is provided with a stick 37 at its bottom to hold it 60 straight and a shield 38 is secured to the frame at the top thereof, the said shield depending below the roller on the inner side of the curtain. The frame is also provided at its bottom and at each end with a rib or 65 ledge 39, the said rib or ledge extending be-

yond the curtain at each side as shown more particularly in Fig. 3, to prevent light passing at the edges or at the bottom of the curtain. It will be noted that the ledge 39 extends above the lower edge of the shield 38.

The frame 2 is provided at its lower side with an upwardly extending partition 41, which extends to the level of the upper face of the floor 3 and the ledge 9, before mentioned, is on this partition. The said partition 70 prevents the entrance of light from below. Cords or straps 40 are arranged at each end of the partition, each cord having one end connected to the stick 37 as shown at 42 and the other end connected to the partition 41, as shown at 43. The said cords 75 limit the closing movement of the curtain to the position shown in Figs. 2 and 3.

The curtain is for use during the insertion or removal of the hands of the operator in 80 the sleeves 35. When the hands are to be removed from the sleeves, the curtain is drawn down until the lower edge thereof is below the floor 3. The admission of light 85 through the sleeves to the interior of the case 90 is thus prevented. When the hands are again introduced into the sleeves, the curtain is raised.

An opening is provided near the ends 6, and the said opening is normally closed by a 95 door 46. The edges of the opening and the edges of the door are rabbeted as shown at 47 so that when the door is in place, it is prevented from dropping through the opening and a tight closure is made. A ring 48 is secured to the door for lifting the same when it is desired to remove it. The rabbeted edge of the opening will also permit the insertion of a tank for hypo, the edges of the tank engaging the said edge to hold 100 the tank in place. When a tray is used for the hypo the door is closed. The bottom is also provided with a transverse rib 49.

In use, that end of the case adjacent to the end 5 is designed to receive accessories, 110 and the door at that end may be opened and closed to insert and remove the said accessories. The said door at the opposite end is intended for the insertion and removal of the different trays used in the work. The 115 opening at the front may be closed by the three sheets, or by the glass alone as may be desired. The hands of the operator are inserted through the sleeves and the operation may be watched through the peep-hole 120 at the top, the operator placing his face against the upper edge of the shield 26. The operation of developing may be carried on inside the case while the operator may inspect the operation and follow it closely 125 from the outside. The device may also be used for printing. When printing velox or similar paper, the printing frame is placed near the window which is opened entirely and the light may be arranged in 130

front of the window. After the print has been exposed a sufficient length of time, the window is closed, and the print may be developed in subdued light. The shield 26 is preferably made so that it may be folded down flat on to the top. After the operator has finished his work, the device may be knocked down and packed in small space. The operation of setting up is preferably 10 conducted as follows: The front 1 and the rear 2 and one end, for instance, the end 6, are first set up, and connected by means of the hinges and the rods. The bottom and the top may now be slid into place after 15 which the end 5 is placed and secured.

It will be evident that the device is comparatively inexpensive, may be easily set up or knocked down, occupies but little space in either position, and is capable of transportation whenever desired. All of the disagreeable features of the dark room, such as over heat, and lack of ventilation are removed. The device can be used with either sunlight or artificial light, and guess-work is entirely eliminated since the entire 20 operation of developing and printing is under the inspection of the operator. The device can also be used for loading of plate holders and the like. It will be understood 25 that the device may be made of any desired size and of any suitable material. The inside is preferably painted of a dark color and the outside may be of any desired color and may be ornamented if desired.

30 It will be noted from an inspection of Figs. 5 and 7, that neither the groove 15 nor the rib 17 extend to the top of the end, the said groove and rib stopping short a short distance from the top.

35 It is not necessary to entirely cut off the light between the face and the edge of the shield, all that is necessary is that the eye be brought sufficiently near to see. The sleeves need not fit the arms closely, and 40 they are made loose to permit the easy insertion and removal of the handle. They may if desired, be folded around the wrist or the arm or be secured by arm bands. The rib 49 is designed to prevent the sliding 45 of the trays toward the portion of the bottom reserved for the accessories and also for preventing water passing. It will be noticed that the sleeves 35 of the hood are inside the hood. With this construction if 50 desired, arm bands may be placed after the hands have been inserted to hold the said sleeves tightly to the arms. The bands may be held in the hand during the insertion of the arms, and may be placed inside the 55 hood.

60 I claim:—

1. A device of the character specified, comprising a case consisting of a front plate and a rear frame, end plates, a top and a 65 bottom, the front and end plates and the

rear frame each having a longitudinal guideway at its upper edge, said guideways registering to receive the edges of the top, said front and side plates and rear frame each having a ledge spaced apart from its bottom edge, said ledges registering for receiving the bottom, the rear frame having an imperforate partition extending to the level of the floor and carrying the ledge, means for detachably connecting the side 70 edges of the ends to the front plate and rear frame, a light proof hood of flexible material connected to the rear frame and having an open sleeve at each end for receiving the hands of the operator, a curtain for closing 75 the opening of the rear frame, the top having an opening near its center, a shield inclosing the opening, the upper edge of the shield being shaped to fit the face, said top having a frame below the opening provided 80 with guideways, sheets of material impervious to the actinic rays within the guideways, said front having an opening near its center, guideways on the inner face of the front above and below the opening, and 85 a plurality of frames slideable in the said guideways, said frames being adapted to hold sheets of material impervious to the actinic rays.

2. A device of the character specified, 90 comprising a case consisting of front and end plates and a rear frame, means for detachably connecting the end plates to the front plate and the rear frame, said front and end plates and the rear frame having 95 registering guideways at their tops, a top plate in the guideways, said front and end plates and the rear frame having registering guideways spaced apart from their bottom edges, and a bottom in the guideways, a 100 hood of light-proof flexible material connected with the rear frame, said hood having open sleeves for receiving the arms of the operator, and a curtain of flexible material impervious to light arranged at the top 105 of the rear frame and capable of being raised and lowered by the operator to shut off the light from the interior of the case when his hands are not in the sleeve.

3. A device of the character specified, 110 comprising a case consisting of front and end plates, a top and a bottom, and a rear frame, means for detachably connecting the front and end plates and the rear frame, said front and end plates and the rear frame 115 having means for supporting the top and the bottom and a hood of flexible material impervious to light connected with the rear frame and having at each end a sleeve for receiving the arm of the operator, and means 120 for closing the frame when the sleeves are opened.

4. A device of the character specified, 125 comprising a collapsible light proof case, the rear of the case having a longitudinally ex- 130

tending opening, a hood of flexible material impervious to light, connected to the edges of the opening and provided at each end with an open sleeve for receiving the hands 5 of the operator, a spring roller journaled at the top of the opening and extending longitudinally thereof, a curtain of flexible material impervious to light, winding on the roller for closing the opening when the 10 sleeves are not in use, said case having an opening in its top, a cover for the opening, said cover transmitting only the non-actinic rays, a shield encircling the opening and shaped at its upper edge to fit the face, said 15 case having a door opening at each end, and a door hinged at each opening.

5. A device of the character specified, comprising a collapsible light proof case, the rear of the case having a longitudinally 20 extending opening, a hood of flexible material impervious to light, connected to the edges of the opening and provided at each end with an open sleeve for receiving the hands of the operator, said case having an 25 opening in its top for permitting the inspection of the interior, a shield for the opening, impervious to the actinic rays, said case having a door opening at each end, a door hinged at each opening, said case having an 30 opening in its front, and a plurality of guideways extending longitudinally of the opening, a plurality of frames slidable in the guideways, said guideways being spaced to permit the frames to slide over the opening, 35 and a screen of material in each frame, impervious to the actinic rays, and means for closing the opening at the rear of the case, said means being operated from the interior of the case.

40 6. A device of the character specified, comprising a collapsible light proof case, the rear of the case having a longitudinally extending opening, a hood of flexible material impervious to light, connected to the

edges of the opening and provided at each 45 end with an open sleeve for receiving the hands of the operator, said case having an opening in its top for permitting the inspection of the interior, a shield for the opening, impervious to actinic rays, said case having 50 a door opening at each end, a door hinged at each opening, said case having an opening in its front, and a plurality of guideways extending longitudinally of the opening, a plurality of frames slidable in 55 the guideways, said guideways being spaced to permit the frames to slide over the opening, and a screen of material in each frame impervious to the actinic rays.

7. A device of the character specified, 60 comprising a collapsible light proof case having an opening in its top and an opening in its front, each provided with a screen of material impervious to the actinic rays, said case having an opening at its rear, a hood of 65 flexible light proof material connected to the edge of the opening and provided at each end with a sleeve for receiving the hands of the operator, said case having door openings at its ends, and doors closing the openings. 70

8. A device of the character specified, comprising a collapsible light proof case having an opening in its top and an opening in its front, each provided with a screen of material impervious to the actinic rays, said 75 case having a plurality of openings at its rear for the hands of the operator, and means for closing the openings at will, said means comprising a spring controlled roller curtain mounted above the opening, and flexible connections between the ends of the lower edge of the curtain and the bottom of the case. 80
